UNITED STATES PATENT OFFICE.

HELUM J. WASHBURN AND EDGAR L. CUDABACK, OF RANSOMVILLE,
NEW YORK, ASSIGNORS OF ONE-HALF TO CLINTON G. CUDABACK
AND WILLIAM G. WASHBURN, OF SAME PLACE.

SPRING-TOOTH HARROW.

SPECIFICATION forming part of Letters Patent No. 611,299, dated September 27, 1898.

Application filed June 26, 1896. Serial No. 597,038. (No model.)

To all whom it may concern:

Be it known that we, HELUM J. WASHBURN and EDGAR L. CUDABACK, citizens of the United States, residing at Ransomville, in the 5 county of Niagara and State of New York, have invented a new and useful Spring-Tooth Harrow, of which the following is a specification.

Our invention relates to harrows, and has 10 for its object to provide an improved construction of spring-tooth harrow of the sectional or folding frame type wherein the folding of the parts or members is facilitated without causing interference between the series 15 of spring-teeth, which in the preferred construction project above the plane of the frame, and, furthermore, to provide a simple and improved construction and arrangement of means whereby the teeth are so attached to 20 the tooth-bars as to resist the various strains applied to the teeth in their different positions.

Further objects and advantages of this invention will appear in the following description, 25 and the novel features thereof will be particularly pointed out in the appended claims.

In the drawings, Figure 1 is a perspective view of a harrow constructed in accordance 30 with our invention. Fig. 2 is a central longitudinal section of the same, taken between the harrow-sections. Fig. 3 is an enlarged detail transverse section of the fastening device for the harrow-teeth. Fig. 4 is a detail 35 sectional view on the line xx of Fig. 3. Fig. 5 is a detail view in perspective of one of the saddle-plates.

Similar numerals of reference indicate corresponding parts in all the figures of the drawings.

The harrow-frame comprises coextensive side sections or members 1, of which the front bars 2 are connected with the outer side bars by rounded portions 5, said round and the 45 parallel rear bars or sides of the frame-sections being extended beyond the inner side bars 6 to form extensions 3, which are overlapped and are pivotally connected by means of pivots 4 to allow the harrow-sections to ad-

just themselves to inequalities in the surface 50 of the soil and also enable one section to be folded upon the other in accordance with the usual practice. The inner side bars 6 of the frame-sections are parallel with the outer side bars and are spaced apart to form a longitudinal interval, into which project the inner ends of certain of the tooth-bars 8, which are mounted in suitable bearings 7 upon the outer and inner side bars. The tooth-bars of the two sections are alined in pairs, but of 55 each pair of alined tooth-bars only one is extended beyond the inner side bar of the frame into the longitudinal space, the extended portions of the tooth-bars being indicated at 8^a. The spring-teeth 19 are arranged upon each 60 tooth-bar at uniform intervals; but the innermost teeth of two alined tooth-bars are arranged at different distances from the medial line of the harrow, or, in other words, a longitudinal line connecting the pivots 4. Thus 65 the corresponding harrow-teeth upon the alined tooth-bars are arranged at relatively-different distances from the medial line of the harrow-frame, whereby when the harrow-sections are folded one upon the other said harrow-teeth are disposed in different vertical 70 planes, and the sections are adapted to fold compactly.

The tooth-bars 8 are preferably of tubular construction, and each is provided upon opposite sides of the plane of each harrow-tooth with transverse bolt-openings 9 (see Fig. 3) for the reception of diametrical bolts 10, fitted with taps or nuts 11, said taps or nuts preferably being arranged at the upper ends of the 85 bolts, whereby they are within reach for adjustment with facility to take up looseness due to jarring or wear. Fitted upon the under side of each tooth-bar between the spaced securing-bolts 10 and in the planes of the harrow-teeth are saddle-plates 15, having upwardly-extending side flanges, which are provided with registering curved seats 16 to snugly fit the contour of the tooth-bars. These saddle-plates are of a length greater 90 than the diameter of a tooth-bar, and at their undersides they are longitudinally channeled to form harrow-tooth seats 17, bounded at 95

- their sides by depending ribs 18. Each harrow-tooth is provided at its inner or fixed end with a straight or flat portion to fit in the harrow-tooth seat 17 of one of the saddle-
 5 plates, and beyond the front end of the saddle-plate said tooth is abruptly curved upwardly to form a runner portion, upon which the harrow may be supported when the feet thereof are inoperative or are turned back so
 10 as to remove their extremities from contact with the soil. The free ends of the harrow-teeth are arranged radially opposite the inner or fixed ends thereof, whereby when said free ends are approximately under the tooth-bars,
 15 being slightly in rear thereof, the straight-seated portions of the teeth are arranged in a horizontal plane. Thus in order to bring the runner portions of the teeth into operative position it is necessary only to turn a tooth-
 20 bar through an angle of ninety degrees.
- Spanning the seats 17 of the saddle-plates and arranged parallel with and beneath the tooth-bars are clip-plates 14, having openings
 25 13, through which the securing-bolts 10 extend, the heads 12 of said bolts being arranged in contact with the under surfaces of said clip-plates, whereby when the bolts are tightened the clip-plates bear against the under surfaces of the flat or straight portions
 30 of the teeth, and thus hold the same firmly in the seats 17 of the saddle-plates and at the same time secure the seats 16 of the saddle-plates in firm frictional contact with the surfaces of the tooth-bars.
- 35 It will be seen that the diametrical disposition of the securing-bolts with relation to the tooth-bars insures the positive fastening of the teeth to said bars and prevents both rotary and longitudinal displacement of not
 40 only the teeth but the saddle-plates; but at the same time a tooth may be readily disconnected from the tooth-bar by simply removing the taps 11 from the securing-bolts. Hence while we have provided an efficient
 45 means of attachment of harrow-teeth to a tubular tooth-bar we have at the same time provided such means as to facilitate the removal and replacement of those teeth. The special advantage in engaging the securing-
 50 bolts with diametrical openings in the tooth-bars, however, consists in the fact that where the teeth describe approximately a complete circle or spiral coil and are adapted at points near their fixed ends to perform the functions of runners it is necessary to provide such means for securing the teeth to the tooth-bars as to prevent twisting or slipping, and the specific means herein described have proved under test to be efficient in all positions of the teeth.
- 55 Rock-arms 20 are detachably bolted or otherwise secured, as at 21, to traverse the tooth-bars near their inner ends, with the exception of the rearmost tooth-bars, which have
 60 fitted thereto near their inner ends adjusting hand-levers 22, provided at one side with suitable catches 23, adapted to engage the teeth or locking-segments 24. Connecting-rods 25 extend from the adjusting-levers to the rock-arms, whereby said rock-arms, with the tooth-bars to which they are attached, may be adjusted simultaneously by applying operating force to the handles. Any suitable draft appliances may be employed, such as clips 26, links 27, connected with the clips, and a draft-
 65 bar 28.
- 70 From the above description it will be seen that the arrangement of the innermost teeth upon alined tooth-bars at different distances from the medial line of the harrow enables us to apply teeth to the inwardly-extending portions of the tooth-bars to occupy the space between the harrow-frames without interfering with the folding of those frames; but it will be understood, furthermore, that in practice various changes in the form, proportion, and the minor details of construction may be resorted to without departing from the spirit or sacrificing any of the advantages of this invention.
- 75 Having described our invention, what we claim is—
1. In a harrow, the combination of a sectional frame of which the members are pivotally connected upon a medial line for folding into planes one above the other, each frame-section having inner and outer side bars, of which the former are spaced apart to form a longitudinal interval, transverse tooth-bars mounted in bearings upon said side bars of the frame-sections, the tooth-bars of one frame-section being respectively alined with the tooth-bars of the other section, and one of the tooth-bars of each pair being extended inwardly beyond the inner side bar of the frame-section to occupy a position in said longitudinal space between the inner side bars, and teeth spaced at uniform distances upon each tooth-bar, with the innermost teeth on alined bars arranged at different distances from the medial line upon which the frame-sections are connected to fold, whereby when the frame-sections are folded, the adjacent teeth are arranged in different vertical planes, substantially as specified.
- 80 2. In a harrow, the combination with a supporting-frame and rocking tooth-bars, together with operating devices for said tooth-bars, of spring-teeth, each consisting of a complete spiral coil provided at its inner end with a straight flat portion, a saddle-plate provided with lateral upwardly-extending flanges cut away at their centers to form registering seats receiving and fitting the contour of a tooth-bar, and also provided at its underside with a longitudinal seat, approximately equal in depth and width with the straight flat inner portion of the teeth, and adapted to receive the same, a clip-plate arranged in contact with the under surface of said flat portion of a tooth and parallel with the tooth-bar, and provided near its ends with openings registering with diametrical openings in the tooth-bar, and securing-bolts extending upwardly through
- 85 90 95 100 105 110 115 120 125 130 135

said registering openings in the clip-plate and tooth-bar and fitted at their upper ends with taps, said bolts being arranged upon opposite sides of the vertical plane of a tooth, and being
5 adapted to hold the saddle-plate from longitudinal and rotary movement with relation to the tooth-bar, substantially as specified.

In testimony that we claim the foregoing as

our own we have hereto affixed our signatures in the presence of two witnesses.
